UNITED STATES PATENT OFFICE.

ALEXANDER W. MACKENZIE, OF MONTCLAIR, NEW JERSEY, ASSIGNOR TO MEAKIN & RIDGWAY, INC., OF NEW YORK, N. Y., A CORPORATION OF NEW YORK.

DESIGN FOR A PLATE OR SIMILAR ARTICLE.

Application filed May 12, 1926. Serial No. 17,661. Term of patent 14 years.

To all whom it may concern:

Be it known that I, ALEXANDER W. MACKENZIE, a citizen of the United States, residing at Montclair, in the county of Essex, State of New Jersey, have invented a new, original, and ornamental Design for a Plate or Similar Article, of which the following is a specification, reference being had to the accompanying drawing, forming part thereof.

Figure 1 is a plan view of a plate show-

ing my new design, it being understood that the border decoration as shown in the drawing, is continued around the article.

Figure 2 is a cross sectional view of the same on the line 2—2 of Figure 1.

I claim:

The ornamental design for a plate or similar article as shown and described.

In testimony whereof I have signed my name to this specification.

ALEXANDER W. MACKENZIE.
